UNITED STATES PATENT OFFICE

2,298,218

PILLOW AND SIMILARLY CUSHIONED ARTICLE

Regnar E. Madson, Chicago, Ill., assignor to Protectoseal Company of America, Inc., Chicago, Ill., a corporation of Illinois

Application June 27, 1940, Serial No. 342,655

3 Claims. (Cl. 5—337)

The invention relates to cushioned articles such as pillows, mattresses and bassinettes, and particularly it relates to cushioned articles of the kind described having thicknesses normally less than their length or width.

An elongated pillow casing of selected dimensions, if filled or stuffed to its unrestricted capacity with cushioning material, is distended thereby to substantially cylindrical shape and likewise, if the casing is approximately square and similarly filled or stuffed to capacity, it is distended to substantially spherical shape or configuration. It is in general desirable and for most purposes practicable that pillows and like cushioned articles have thicknesses less than their length or width, and the invention has among its objects the provision of novel means adapted to limit the maximum possible thickness of a cushioned article of the kind described to dimensions substantially less than its width or length and without impairing its cushioning qualities or preventing it from being crushed, bent, turned, reclined, doubled or otherwise distorted as the user may desire.

Since materials such as feathers, down, and the like hitherto generally used as cushioning material for pillows and similarly cushioned articles tend to give off dust to which many persons are hypersensitive or allergic and a selected amount of such materials has no fixed volume by reason of the individual particles thereof being fluffy and tending to spread out, the invention has as another of its objects the provision of dustless cushioning material made up of a plurality of particles, elements or flakes preferably of various sizes, the individual particles being characterized by their having a normal fixed configuration and the lack of any tendency to expand or change their shape other than when they are compressed or otherwise distorted. Among the materials adapted for cushioning purposes and having the above designated desirable characteristics may be included cellular latex rubber, sponge rubber, or any other form of rubber or material of similar texture and having like qualities and resiliency when compressed or otherwise distorted whereby when a casing or other single receptacle is filled to capacity therewith, such materials are undistorted and have their maximum initial resiliency and cushioning qualities.

A further object of the invention is the provision of a pillow or similar cushioned article having cushioning material so enclosed and of a character such that the material does not dis-

seminate any dust particles to which the user may be hypersensitive or allergic.

Another object of the invention is the provision, in pillows having a plurality of dustless, porous, resilient particles as cushioning material, of an improved receptacle or casing for such materials whereby the casing does not retard or interfere with the yielding or so-called "breathing" properties of the enclosed material.

10 A further object of the invention is the provision of improvements in pillows and similar articles comprising an inner cushion and an outer closed slip, the improvements adapting the pillow to be washed and dried intact, centrifugally or otherwise without affecting its normal configuration, cushioning or flexible qualities.

A further object of the invention is the provision of improvements in pillows and similar cushioning articles adapting the same to be distorted and to remain in any suitable or desired distorted position or configuration and to retain their full flexibility and cushioning qualities unimpaired in any and all such positions.

Still another object of the invention is to provide improvements in pillows and similar articles of the kind described, said improvements being easily constructed, durable, and satisfactory for their intended purpose.

Many other objects and advantages of the construction herein shown and described will be obvious to those skilled in the art.

Referring now to the drawing wherein like reference characters indicate like or corresponding parts:

35 Fig. 1 is a plan view partially in section of a pillow embodying the principles of the invention;

Fig. 2 is a view along the line 2—2 of Fig. 1; and

Fig. 3 is a view along the line 3—3 of Fig. 2.

40 Referring now more particularly to the drawing, the invention is illustrated as embodied in a pillow generally designated by the numeral 10 and comprising an outer slip 11, cushioning material 12, and an open or network casing 13 forming a closed receptacle for the cushioning material.

As above suggested, the cushioning material 12 consists of a plurality of dustless particles or elements of resilient material of various sizes. Rubber of the type commonly called cellular latex, and sponge rubber or any other form of rubber prepared for this purpose by grinding, shredding, cutting, flaking and the like, is preferably used, the particles being of any suitable size from the smallest which may be retained by the net-like casing 13 to relatively large particles

having the requisite cushioning properties. The amount of cushioning material used varies with the dimensions of the pillow and is preferably such that the casing 13 is as nearly completely filled as possible to the configuration indicated in Figs. 2 and 3 without initial compression of any of the particles or elements comprising the material, or in other words the casing is loosely filled.

The outer slip 11 is constructed of any suitable fabric material such as linen or cotton sufficiently closely woven to be substantially impervious to the passing of dust particles therethrough under normal usage. The slip 11 has a closely stitched marginal hem 14 preferably in-turned along one longitudinal edge and across one end, the hem being out-turned across the other end for convenience in opening and closing to permit insertion and removal of the casing 13 containing the cushioning material 12.

The casing material 13 may be closely woven but it preferably consists of interwoven threads which may be of any desired color and of any texture suitable for weaving. The threads comprising the casing material 13 may be as closely spaced as 140 to 180 per inch or the casing may be coarser and the spacing of the threads much greater, but sufficiently close that the casing retains the finer particles of the cushioning material 12. The wider or net-like spacings of the threads comprising the casing 13 are desirable as they permit free ingress and egress of air to the cushioning material 12, or in other words, the so-called "breathing" characteristics of the cushioning material are not impaired by an open-work casing.

The casing 13 may be made from a single sheet of material cut and folded to a double thickness of rectangular shape as shown with its contiguous edges connected by stitches to provide an out-turned hem 16, or if preferred, the sheet may be cut and similarly folded to provide a casing having round corners.

A casing 13 of given or selected lateral and longitudinal dimensions, if filled with cushioning material to its maximum capacity, will be distended to a substantially cylindrical shape instead of being relatively flat as ordinarily made. As shown in Figs. 2 and 3 of the drawing, the capacity of the casing 13 is limited by and prevented from being distended to cylindrical form when filled to such limited capacity by means of bands or tie members connecting opposite sides of the casing. The tie members are provided to limit the permissible amount of spread or spacing between the opposite sides of the casing 13 and thereby to control the amount of distension and the thickness of the casing and of the pillow 10 as a whole.

Only two tie members respectively designated by the numerals 17 and 18 are shown in the drawing, but obviously, any other number may be provided if desired. The maximum amount of uncompressed cushioning material that a casing 13 equipped with the tie members 17 and 18 is adapted to contain obviously depends not only on the longitudinal and lateral dimensions of the casing, but also upon the lengths and the arrangement of the tie members 17 and 18. Referring to Figs. 2 and 3, wherein the casing 13 is illustrated as filled with cushioning material 12 to its said limited maximum capacity with the elements or flakes comprising the cushioning material uncompressed, it is apparent that the tie members 17 and 18 tend to hold the casing 13 to the configuration shown when so filled. The

opposite ends of each of the tie members 17 and 18 are fastened together in any suitable manner such as by tying or by stitching to form corresponding continuous members of suitable length. The tapes or bands 19 respectively stitched or otherwise fastened to the opposite sides of the casing 13 and similarly spaced from the marginal edges thereof are arranged in the form of rectangles preferably of the same dimensions. Similarly, two tapes or bands 20 are respectively fastened to opposite sides of the casing 13 and extend longitudinally thereof and are preferably so positioned as to bisect the rectangular spaces provided by the bands 19. A plurality of loops 21 are fastened to each of the bands 19 and 20. The tie member 17 forms a lacing extending through a loop 21 fastened to a band 19 on one side of the casing, then through a corresponding loop 21 fastened to a band 19 on the other side of the casing. The tie member 17 is in turn laced through all of the loops 21 of the bands 19, the lacing being as shown in Fig. 2 and being of such a length that it is substantially taut when the casing is filled to desired capacity without compressing the cushioning material 12 at the thickness and for the general configuration of the casing shown. Likewise, the continuous tie member 18 is laced through the casing 13 by extending it through all of the loops 21 on the oppositely positioned bands 20, the arrangement being as shown in Fig. 3 and similar to the arrangement of the member 17. The end loops 21 on the bands 20 are spaced slightly away from the contiguous portions of the bands 19. The spacings of the loops 21 on the bands 19 and 20 are substantially equal and preferably less than the maximum permissible thickness of the casing 13 when filled and in its normal configuration with the cushioning material undistorted. The described spacings of the loops 21 are such that the tie members 17 and 18 limit the flow of the cushioning material 12 when the pillow is in use and permits substantially free flow thereof during manipulation or distortion of the pillow in the manner commonly called "fluffing." Obviously, when the casing 13 is filled with cushioning material 12 as described and with the tie members 17 and 18 drawn substantially taut, the pillow will normally tend to retain the configuration shown in cross section in Figs. 2 and 3. The tie members limit the thickness to that shown and the cushioning material tends to hold the tie members relatively taut except when such material is compressed or otherwise distorted by use. Without some means such as the continuous longitudinally movable tie members 17 and 18, the limited amount of cushioning material would not be held by the casing 13 in a compact undistorted bulk, but would tend to flow in the casing and upon manipulation, the casing would be only partially filled. The tie members 17 and 18 being free to move relative to the loops 21, are self-adjustable to permit easy manipulation of the pillow from undistorted to any distorted position or from one distorted position to another or from a distorted position back to its normal configuration.

Thus, it will be seen that I have provided an article such as a pillow or the like having cushioning material of improved desirable characteristics and novel means for limiting the capacity of a casing containing such cushioning material whereby the pillow is always relatively compactly filled and the resiliency and cushioning qualities thereof are increased.

Having thus described my invention, it will be

obvious that various immaterial modifications may be made in the same without departing from the spirit of the invention; hence I do not wish to be understood as limiting myself to the exact form, construction, arrangement and combination of parts herein shown and described or uses mentioned.

What I claim as new and desire to secure by Letters Patent is:

1. In an article of the kind described, a casing providing a receptacle for cushioning material, a plurality of loops disposed within and fastened to one side of the casing and a corresponding number of loops disposed within and fastened to the opposite side of said casing, two continuous tie members each successively extending through a loop on one side of the casing and then through a loop on the opposite side of said casing, said tie members being adapted to limit distension of the casing and to correspondingly limit its capacity and its thickness when filled to said limited capacity, one of said tie members extending around the casing at a uniform distance from the marginal edges thereof and the other extending along a substantially median line thereof, said tie members being adapted to be moved longitudinally relative to all of the loops with which said members are respectively connected, and a body of undistorted cushioning material loosely filling said casing to said limited capacity, said cushioning material comprising a plurality of resilient particles having fixed dimensions when unconfined and undistorted.

2. In an article of the kind described, a casing providing a receptacle for cushioning material, two continuous longitudinally movable tie members connecting the opposite sides of said casing at a plurality of points adapted to limit its distension and to correspondingly limit its capacity and the thickness thereof when filled to said limited capacity, a body of undistorted cushioning

material of the kind described loosely filling said casing to its limited capacity, a plurality of loops fastened to opposite sides of said casing, one of said tie members being successively laced through a loop on one side and then through a loop on the other side of the casing, said loops being so arranged that said tie members extend around said casing at a distance from the marginal edges thereof, the other of said tie members being similarly laced through the remaining loops along a substantially median line of the casing, said tie members being adapted for unlimited longitudinal movement through each of the loops with which they are respectively connected.

3. In an article of the kind described, netting arranged to provide a closed casing or receptacle, resilient cushioning material loosely filling said casing, a plurality of loops disposed within the casing and fastened to opposite sides thereof in spaced apart relation along lines forming boundaries of substantially quadrangular areas on each of said opposite sides, a plurality of loops similarly disposed within the casing and fastened to opposite sides thereof along the median lines of said areas, a continuous tie member threaded alternately through a loop on one side and then through a corresponding loop on the other side of the casing to provide a lacing connecting all of the loops so arranged along boundary lines of said areas, a second continuous tie member threaded alternately through a loop on the median line on one side and then through a corresponding loop on the median line on the other side of the casing to provide a lacing connecting all of said median loops, said tie members each being freely movable longitudinally relative to the sides of the casing and their length being such as to limit the thickness of the casing relative to its width and length when loosely filled with cushioning material.

REGNAR E. MADSON.
